[57] **CLAIM**

The ornamental design for a massage tool, as shown and described.

DESCRIPTION

FIG. 1 is a perspective view of a first embodiment of a

massage tool showing my new design;

FIG. 2 is a bottom view thereof;

FIG. 3 is a top plan view thereof;

FIG. 4 is a front side elevational view thereof; the left side, rear side and right side elevational views being identical;

FIG. 5 is a perspective view of a second embodiment of a massage tool;

FIG. 6 is a bottom view thereof;

FIG. 7 is a top plan view thereof;

FIG. 8 is a front side elevational view thereof; the left side, rear side and right side elevational views being identical;

FIG. 9 is a perspective view of a third embodiment of a massage tool;

FIG. 10 is a bottom view thereof;

FIG. 11 is a top plan view thereof;

FIG. 12 is a front side elevational view thereof; the left side, rear side and right side elevational views being identical;

FIG. 13 is a perspective view of a fourth embodiment of a massage tool;

FIG. 14 is a bottom view thereof;

FIG. 15 is a top plan view thereof; and,

FIG. 16 is a front side elevational view thereof; the left side, rear side and right side elevational views being identical.
